UNITED STATES PATENT OFFICE

JOHN GUNDERSON, OF CONCRETE, WASHINGTON

CLOSURE OPERATOR

Application filed September 24, 1928. Serial No. 308,011.

This invention pertains to new and useful improvements in closure operators and more particularly to means for remotely operating the doors of garages, barns, and the like. Closure operators of this character have been heretofore devised with this attainment in view, but because of intricate and cumbersome mechanism, these operators have met with but slight use. It is the aim of this invention to overcome the deficiency of the present type of door operators by providing an operating mechanism which will be positive in operation and which employs but a limited number of parts.

The prime object of this invention resides in the provision of a door operator having means whereby the door may be either opened or closed from a remote exterior point.

Another object of importance resides in the provision of a single operative mechanism which can be made to serve the purpose of operating double doors without in any manner interfering with the part thereof.

Still another object is to provide a door operator positive in operation and wherein because of the peculiar association of parts, the same is not susceptible of quick wear but will be exceedingly durable in use.

After considering the following specification and claim other important objects and advantages of the invention will become apparent.

In the drawings:—

Figure 1 represents a vertical section through a conventional door frame showing the usual door mounted upon novel structure included in the present invention and being also shown in closed position with respect to the door frame.

Figure 2 represents a similar view fragmentarily showing the door in open position and further showing the operable parts of this invention in inverse order.

Figure 3 is an enlarged fragmentary longitudinal sectional view through the conduit through which the actuating strands for actuating the operable parts of the invention are trained.

Figure 4 represents a fragmentary outside

elevation of the door in closed position with respect to the present invention.

Figure 5 is an inside fragmentary elevation showing the parts in substantially the same position as in Figure 4.

Figure 6 illustrates a horizontal sectional view through the door frame disclosing in plan view the connection of a pair of hinged doors in association with the present invention.

Figure 7 is a top plan view of the cam body upon which the door is supported, and,

Figure 8 represents a vertical fragmentary sectional view therethrough.

Referring to the drawings wherein like numerals designate like parts, the usual jam portions 1—1 of the usual door frame construction has a stop piece 2 interposed between the upper end portions thereof and against which the door 3 is adapted to engage for limiting the inward movement thereof so that the same may be maintained in a closed position with the assistance of the present invention which will be fully described hereinafter. This door may be of the twin or double type including the sections 4—4.

One of the door sections 4 is provided with straps 5—5 which are looped around a vertical hinge bar 6.

A body 7 is formed with an opening 8 through which the bar 6 extends, and this body 7 is secured to one jam portion of the door frame in the manner clearly shown particularly in Figure 4. The top of this body is inclined in opposite directions from a high point 9. These inclined surfaces are substantially flat. The body 7 is curved at its upper portion of its outer side.

An arcuate substantially semi-circular plate 10 is rockably mounted on the body 7. The plate 10 is provided intermediate its ends with a depending boss 11 through which a pin or in fact any suitable member 12 extends for securing the boss to the body at its high point 9 and in a manner whereby the plate 10 may be tilted to bear against either of the inclined surfaces of the body 7 extending from the high point 9. Each end

of the plate 10 is provided with an upwardly inclined arm extension 13.

An elongated conduit 14 of hollow construction is secured at one end portion to the upper portion of the door frame and is adapted to extend outwardly from the building for a predetermined distance. Mounted within the conduit is an upper and a lower set of rollers 15. Over the lower set of rollers a flexible strand 16 is trained and is connected at one end to one of the arms 13, while its opposite end depends below the conduit 14 in the manner clearly shown in Figure 1. A second strand 17 is trained over the upper set of rollers and extends over the doorframe and into the inside of the building for connection to the opposite arm 13. The outer end portion of this strand likewise depends below the conduit 14.

The door section 4 is formed at its hinged edge portion, with an opening 18 at the upper edge of which a roller 19 is mounted and adapted to bear upon the rocker bar plate 10 for supporting the door section. An arm 20 projects inwardly from the hinged edge portion of one of the door sections 4-4 and has one end of an elongated connecting bar 21 pivoted thereto at its opposite end, while the opposite end of the connecting bar is pivotally connected to the opposite door section 4. Obviously a movement of the first mentioned section will result in a relative movement of the other.

A gradually rising rib 22 is located on the outer end portion of the rocker plate 10, and is shown in Figures 1, 2, 6 respectively.

Assuming that the door frame is in the closed position as shown in Figure 1. In this position the roller 19 is bearing on the rocker plate 10 at a point inwardly from the supported point thereon. Obviously, in this position the door will have the tendency to gravitate inwardly on the plate and will be thus maintained in closed position against the stop piece 2. When it is desired to open the door, the strand 17 is pulled downwardly at its outer depending end portion which will result in the lifting of the innermost arm 13, at the inner end of the rocker plate 10. This will obviously result in tilting of the rocker plate to an inverted position permitting the door 3 to gravitate down the inclined plate 10 to rest upon the substantially horizontal top of the rib 22 as the roller 19 engages the low end of the rib and starts to move over the same toward the high end of the same, the door is gradually checked in its movement so that said rib acts as a check to the opening movement of the door. The supporting roller 19 minimizes wear and promotes the efficiency of operation of the mechanism.

To again close the door, the strand 16 is pulled at its outer end which results in the lifting of the outer end portion of the rocker plate 10 and the consequent inverse inclined

positioning of the plate 10, whereby the door will be permitted to gravitate to the position assumed in the first instance.

Obviously by reason of the arm 20 and the connecting arm 21, both sections of the door 3 will operate in unison.

It is understood that certain changes in the shape, size or materials may be resorted to in the construction of this mechanism without departing from the spirit of the invention or the scope of the appended claim.

Having thus described my invention, what is claimed as new is:

A door operator comprising a swingably mounted door, a hinged edge portion of the door being provided with an indenture, a roller on the door enclosed within said indenture, an arcuate-shaped track, a support adapted to be mounted on a stationary structure adjacent the door so that its bulk will be accommodated by the indenture in the door, the upper portion of said support being provided with inclined surfaces leading toward an intermediate high point, a rockable connection between the middle portion of the track and the intermediate high point of the support, said roller being adapted to ride on the said track, and means for tilting the said track so as to change the inclination of the said track and a rib on the outer part of the track gradually sloping downwardly from one end of the track to a point adjacent the center thereof, said rib being engaged by the roller and acting as a check to the opening movement of the door.

In testimony whereof I affix my signature.

JOHN GUNDERSON.
